Fig. 9

Fig. 10

FIG. 1 is an enlarged outside perspective view of a lens for a sewing machine light, showing our new design,

FIG. 2 is an enlarged inside perspective view of the lens shown in FIG. 1,

FIG. 3 is a plan view, on a smaller scale, of the inside of the lens shown in FIGS. 1 and 2,

FIG. 4 is a view as seen from the left end of FIG. 3,

FIG. 5 is a view as seen from the front side of FIG. 3,

FIG. 6 is a view as seen from the right end of FIG. 3,

FIG. 7 is a view as seen from the rear side of FIG. 3,

FIG. 8 is a plan view of outside of the lens shown in FIGS. 1, 2 and 3,

FIG. 9 is a sectional view taken on the line 9—9 of FIG. 3, and

FIG. 10 is a sectional view taken on the line 10—10 of FIG. 3.

We claim:

The ornamental design for a lens for a sewing machine light or similar article, substantially as shown.
